UNITED STATES PATENT OFFICE.

FRITZ KADE, OF SANDUSKY, OHIO.

BORING-MACHINE.

SPECIFICATION forming part of Letters Patent No. 269,553, dated December 26, 1882.

Application filed May 24, 1882. (No model.)

To all whom it may concern:

Be it known that I, FRITZ KADE, of Sandusky, in the county of Erie and State of Ohio, have invented new and useful Improvements in Portable Boring-Bars; and I do hereby declare that the following is a full, clear, and exact description thereof, reference being had to the accompanying drawings, which form a part of this specification.

10 The nature of this invention relates to certain new and useful improvements in that class of boring-machines wherein the cutter-bar revolves, and also slides with an endwise motion, the work being at rest.

15 The object of my invention is to construct a very compact, simple, and handy tool, especially adapted to cut or recut tapering holes for wrist-pins in cranks, pitman-rods, &c., without removing the work from its position and 20 leaving it to the skilled workman to secure the tool to the work by any kind of temporary support or clamps, as the circumstances will suggest, all as more fully hereinafter described.

Figure 1 is a vertical central section of my 25 improved tool. Fig. 2 is a perspective view of the head-stock with the adjustable cutter-bar bearing. Fig. 3 is a similar view, but from the opposite or inner side. Fig. 4 is a vertical cross-section of the parts shown in Figs. 2 and 30 3. Fig. 5 is a perspective view of the ball bearing head-stock. Fig. 6 is a perspective view of the cutter-head. Fig. 7 is a perspective view of a support for the head-stocks.

In the accompanying drawings, A is the cutter-bar, provided for a part of its length with 35 a feed-screw, *a*, and its whole length with the groove *b*.

B is a head-stock, which, in the operation of the tool, is held in a fixed position. It forms a 40 ring support for the bearing C, which is adapted to be rotated therein.

D is a square box, adjustably secured in the bearing C, and the opening within which it rests is oblong in cross-section and admits of 45 adjusting the box either centrally or eccentrically to the bearing C, four set-screws, *c c d d*, being used to hold the box in its adjusted position. The set-screws *d d* are attached to 50 sliding plates *e*, with their lower ends engaging in corresponding recesses upon the sides of the box D, so that however the latter is

shifted in its position the set-screws *d d* can be made to bear centrally against its sides. The box D has a central bore, *g*, of proper size to allow the cutter-bar A to freely slide through it, the spline *f* engaging with the groove in the cutting-bar. The box D terminates upon the inner side in the feed-cam E, upon the face of which the feed-pawl F is forced to travel.

G is the feed-nut, and its hub is provided with 60 a female screw engaging with the feed-screw of the cutter-bar, while its cogs engage with the pawl F whenever the latter drops into the cut-away portion *h* of the cam E.

H is a cutter-head, to which the cutting-bit I 65 is secured in the usual manner. This cutter-head is threaded upon the cutter-bar, and can be secured upon the same in any desired position by means of the set-screw *i*.

J is a head-stock supporting the other end 70 of the cutting-bar. It forms a bearing for the ball-box K, through which the cutter-bar is allowed to slide freely.

In practice, the parts being constructed as described, the cutter-bar is passed through the 75 hole upon which the work is to be done; then the head-stocks are secured in temporary supports, which are clamped or bolted to the work. In Fig. 7 is shown a very simple support, L, for the head-stocks, which will be found serviceable for most kinds of work, the set-screws *k* allowing the head-stock to be nicely adjusted, 80 while the bolts *l* will securely clamp the device to the work. Now, if the box D is adjusted eccentrically within the bearing C, the latter, 85 on being rotated, will impart a conical motion to the cutter-bar, the apex of the cone being located in the center of the ball-box K, and if the cutter is adjusted to perform the work it will cut a tapering hole, the cutter-bar A being 90 pushed laterally at every revolution of the bearing C by means of the feed-nut G, cam E, and pawl F, which act in a well-known manner.

No particular devices for rotating the bearing C are shown in the drawings; but in 95 most instances it will be found convenient to secure a gear-wheel upon the part *m* of the bearing C and rotate it by means of a crank and pinion. The operator of course can in every instance make the tool cut any taper he 100 wishes by properly adjusting the two factors which regulate it—viz., the distance between

the head-blocks and eccentricity of the box D. If the latter is secured in the axial center of the bearing C, the tool will bore a hole with parallel sides. In adjusting the head-blocks 5 upon the work care should be taken to make their axial centers coincide with the center of the bore to be cut or recut.

The invention is designed as an improvement upon the device set forth in Patent No. 105,265, 10 of 1870, as specifically pointed out in the claims.

It will be understood that the box D is adjustable in the bearing C to give the desired angle to the cutter-bar. Motion being given to said cutter-bar, and the pawl F being engaged with the nut G to hold it stationary, it follows that the cutter-bar will have longitudinal movement until the said pawl F is forced out of such engagement by the cam E, which action stops the feed.

20 What I claim as my invention is—

1. In a tool for cutting taper holes, a cutter-bar having a feed-screw and a longitudinal groove, a feed-nut, a pawl engaging with said nut to hold it still, and thus cause the cutter-bar to have a longitudinal movement, and a 25

cam for releasing said pawl, combined with an eccentrically-adjustable bearing having internal spline, and a head-stock with a circular interior bearing, as and for the purpose set forth.

2. In a tool for cutting taper holes, the combination of the head-stock B, circular bearing C, provided with devices for rotating it, eccentrically-adjustable bearing D, stationary set-screws c, and laterally-adjustable plate or nut 35 e and set-screw d, all combined substantially as described.

3. In a tool for cutting taper holes, the combination of the cutter-bar A, having feed-screw a and groove b, with cutter-head H, feed-nut 40 G, pawl F, and cam E, and with the box D, having spline f, as and for the purposes set forth.

In testimony that I claim the above as my invention I have herenuo affixed my signature this 27th day of March, 1882.

FRITZ KADE.
